A. HANSEN

LIGHTING FIXTURE

Filed Sept. 20, 1923

正言集

WITNESSES

A technical drawing of a mechanical assembly, likely a lock or fastener. The drawing shows a central vertical shaft with a threaded top and a base. A circular plate is attached to the shaft, featuring several holes and a central slot. Various numbers are used to label different parts and features: 27, 25, 7, 24, 29, 26, 27, 25, 30, 28, 6, 51, 25, 51, 52, and BY. The drawing is oriented horizontally, with the top of the shaft pointing towards the left.

UNITED STATES PATENT OFFICE.

ALFRED HANSEN, OF GLOBE, ARIZONA.

LIGHTING FIXTURE.

Application filed September 20, 1923. Serial No. 663,836.

To all whom it may concern:

Be it known that I, ALFRED HANSEN, a citizen of the United States, and a resident of Globe, in the county of Gila and State 5 of Arizona, have invented a new and Improved Lighting Fixture, of which the following is a full, clear, and exact description.

This invention relates to improvements in 10 lighting fixtures, and has particular reference to a portable lamp stand.

An object of the invention is to provide an improved lamp stand and fixture of such construction that the same may be supported 15 upon a table, suspended from a ceiling, or hung upon a wall, thus making it possible to have the device conveniently located in any desired position.

The above and other objects will appear 20 more clearly from the following detail description, when taken in connection with the accompanying drawing, which illustrates a preferred embodiment of the inventive idea.

In the drawing—

25 Figure 1 is a side elevation, partly broken away and shown in section, of the lighting fixture constructed in accordance with the invention;

Figure 2 is a section on the line 2—2 of 30 Figure 1;

Figure 3 is a section on the line 3—3 of Figure 1;

Figure 4 is a section on the line 4—4 of 35 Figure 1; and

Figure 5 is a plan view of a clamp utilized in supporting the fixture on a wall.

Referring more particularly to the accompanying drawing, the numeral 6 indicates a base of the fixture which may be 40 utilized to support the same upon a table. Extending upwardly from the base 6 is a tubular standard 7, the upper extremity of which has secured thereto an eye member 8 which may be engaged with a hook or other 45 device to suspend the fixture from the ceiling.

An upper bracket member 9 is slidably 50 mounted upon the standard 7 so as to be adjustable thereon and secured in its adjusted positions by means of a set screw or other fastening device 10. A portion of the bracket member 9 extending on one side of the standard 7 is provided with a head 11 having a longitudinal slot 12 therein extending 55 to the outer extremity of said head for receiving one end of a clamping member

13 formed of a flat piece of suitable material. Said end of the clamp 13 is provided therein with a longitudinal slot 14 for receiving a bolt 15 which extends transversely through 60 the head 11 and which has the wing nuts 16 threaded thereon for the purpose of securing the clamp in adjusted position. The outer extremity of the clamp 13 is bent to provide the curved gripping portions 17 de- 65 signed to engage the ordinary picture moulding 18 for the purpose of supporting the fixture on a wall. By making the clamp 13 adjustable with respect to the head 11 it will be apparent that the fixture may be sup- 70 ported in a vertical position with the edge of the base 6 in engagement with the wall regardless of any irregularities in said wall.

A portion of the bracket member 9 on the opposite side of the standard 7 from the head 11 is provided with the usual incandescent lamp socket 19 having a connection 20 at its inner end through which extends a lamp cord 21, one end of which is connected to any suitable form of terminal 22, preferably secured centrally of the ceiling of a room, the cord being of sufficient length to permit of the fixture being moved to any convenient place about the room. 75

The lamp cord 21 in addition to being 80 connected to the socket 19 is extended through the connection 20 and joined to a second lamp socket 23, which is supported in a lower bracket member 24 also adjustably carried by the standard 7. The bracket 90 24 is bifurcated to form a pair of jaws 25 between which the standard 7 is received so that the bracket may be secured in various adjusted positions by means of the bolt 26 and wing nuts 27. A supporting member 28 is detachably secured to the bracket 24 and is provided with a pin 29 extending into said bracket and engaged by a set screw 30 utilized in securing said supporting member in position. The supporting member further includes a pair of arms 31 arranged in spaced parallel relation and designed to receive therebetween a portion of a lamp socket 23 which is pivotally mounted 95 between said arms by means of the screws 32 whereby to enable the socket 23 to be swung about a horizontal pivot to various angular positions with respect to the vertical. 100

What is claimed is:

1. In a portable lamp fixture, a base for supporting the fixture on a table or other 110

support and capable of engagement with a wall, a standard extending from said base, a lamp carrying bracket adjustable longitudinally of said standard and having a bifurcated head at one end, a moulding engaging clamp adjustably mounted in the bifurcated end of said head and having moulding engaging portions at its free extremity, and means extending transversely through 10 said head and said clamp for securing the latter in adjusted positions in said head.

2. In a portable lamp fixture, a base capable of engagement with a wall, a standard extending from said base, brackets adjust-

able longitudinally of said standard, a clamp 15 carried by one of said brackets and capable of engagement with a moulding to support said standard in a vertical position, adjustable toward and away from the standard and cooperating with the base to support said standard in a vertical position, lamp sockets carried by said brackets, means for pivotally supporting one of said lamp sockets with respect to its associated bracket, a connection also carried by one of said brackets, and a conductor extending through 20 said connection and connected to said sockets.

ALFRED HANSEN.
